United States Patent Office

Des. 196,395
Patented Sept. 24, 1963

196,395

IMAGE PROJECTOR

Joel W. Bravo, Binghamton, N.Y., assignor to General
Aniline & Film Corporation, New York, N.Y., a corpo-
ration of Delaware

Filed June 21, 1961, Ser. No. 65,670

Term of patent 14 years

(Cl. D61—1)

FIG. 1

FIG. 2

FIG. 1 is a front, perspective view of an image projector, showing my new design, the side opposite that shown being substantially a mirror image of the side shown; and FIG. 2 is a rear, perspective view thereof.

I claim:

The ornamental design for an image projector, substantially as shown and described.
